UNITED STATES PATENT OFFICE.

THOMAS AUSTIN MITCHELL, OF RIDGEWOOD, NEW JERSEY, AND KEBE TOABE, OF NEW YORK, N. Y.

METHOD OF MAKING ARSENATES.

Application filed July 21, 1922. Serial No. 576,627.

To all whom it may concern:

Be it known that we, THOMAS AUSTIN MITCHELL and KEBE TOABE, citizens of the United States of America, residing at Ridgewood, in the county of Bergen, State of New Jersey, and New York city, in the county of New York and State of New York, respectively, have invented certain new and useful Improvements in a Method 10 of Making Arsenates, of which the following is a full, clear, and exact specification.

Our invention relates to the manufacture of arsenates and more particularly to an improvement over the methods set forth in 15 the prior patents to T. A. Mitchell, Numbers 1,183,315 and 1,183,316, of May 16, 1916.

In the first Patent #1,183,315, Mitchell has disclosed a method of making arsenate 20 by treating arsenic trioxide with strong nitric acid in the presence of metallic lead. According to this method, the trioxide, known as white arsenic, is oxidized by nitric acid to arsenic acid. At the same time, lead is 25 dissolved as lead nitrate which in solution reacts with the arsenic acid to form a precipitate of lead arsenate. Since this reaction depends upon the continuous addition 30 of nitric acid to a mixture of lead and the trioxide, the amount of water in the bath increases and the concentration of the arsenic acid solution therefore progressively decreases. Coincident with this increasing 35 dilution, we find that while at the beginning of the process a finely divided and flocculent precipitate is obtained, the physical condition of the arsenate changes as the reaction proceeds and the product soon appears as a heavy flaky scale adhering to the 40 metallic lead, which form is not well adapted for commercial use.

In accordance with the method set forth in the other patent, the lead arsenate is formed by employing originally the higher 45 oxidation product, arsenic acid, and treating an aqueous solution thereof with nitric acid in the presence of metallic lead. The concentration of the solution of arsenic acid is at first high, but as the reaction proceeds 50 and arsenic is removed from the solution, the concentration is likewise diminished with the objectionable results as noted in connection with the first patent, i. e., obtaining an undesirable form of precipitate.

In the second method, one may resort to 55 heat to evaporate the water and maintain the solution concentrated but this obviously has many disadvantages, due not only to the expensive procedure involved and the wear and tear on the apparatus but also to the 60 fact that the unit cannot work to full capacity or efficiently, as is particularly true toward the end of the process when the amount of liquid is small and the mass of the solids proportionately large.

It is accordingly an object of our invention to remedy such difficulties and avoid the formation of objectionable types of precipitate, and particularly to provide a simple, 70 economical and practicable method of forming metallic arsenates as a finely divided or flocculent precipitate which come down continuously in a substantially uniform physical condition.

With this and other objects in view as 75 will be apparent in the following disclosure, our invention resides in the steps of the process set forth in the following description and covered by the claims appended 80 hereto.

In the course of our experimentation we have discovered that it is desirable and feasible to start initially with a concentrated arsenic acid solution and to maintain its concentration during the formation of the 85 arsenate by replenishing the arsenic in solution as the arsenate precipitate is formed, and we may accomplish this by continuously adding arsenic trioxide to the bath and there oxidizing it to the higher form for reaction 90 with a desired metal element to form the arsenate. The rates of oxidizing arsenic trioxide and of converting it to the arsenate are so regulated as to keep the concentration of the arsenic acid solution substantially 95 uniform. To this end we introduce the desired metal element into the reaction zone at such a rate as to remove arsenic acid from the solution only as fast as it is being replenished by oxidation of the arsenic 100 trioxide. The metal element may be introduced into the bath in the form of a metal, such as lead, in a finely divided state, or it may be in a compound, such as lead oxid. For the purpose of bringing such metal element into the reaction, the bath contains a 105 suitable solvent for the material employed and we prefer that the solvent be capable

also of oxidizing the arsenic trioxid. While we may use such solvents as acetic and formic acids we preferably employ nitric acid due to its ability to serve as a catalyst 5 or carrier of the metal element and at the same time oxidize the trioxid without forming undesirable end products. If solvents, such as acetic acid, are used, we of course employ an oxidizing agent, such as nitric 10 acid, in addition, but preferably use the latter alone.

As one application of our invention we may form a metallic arsenate, such as lead arsenate, by feeding a mixture of arsenious 15 oxid and lead in a suitable form, such as metallic lead or lead oxid, but preferably metallic lead in a finely divided condition, to an aqueous bath of concentrated arsenic acid containing the necessary quantity of 20 nitric acid. The arsenic acid solution (ordinarily 65° to 68° Baumé) is utilized at such a concentration as is sufficient to prevent the precipitate coming down in other than a finely divided form but it is preferably 25 weaker than a saturated solution, since the latter tends to crystallize out at the working temperature of the process and necessitate additional washing of the final product to free it from the unconverted material. The concentration of the bath may 30 be maintained uniform by regulating the rates at which the various reagents are fed thereto. Introduction of an excess of lead, depending upon its rate of solution, tends 35 to withdraw arsenic acid from the bath and reduce the concentration, while the addition and oxidation of more trioxid replenishes the arsenic. Thus, we may, by utilizing 40 suitable apparatus, as is well known in the art, effect a continuous operation of the process by starting with a solution of the desired acid strength and concentration of arsenic acid and then feeding the dry ingredients thereto at the required rate, while 45 continuously removing the precipitate and nitrogen gases for filtration and reuse respectively.

As a specific example of a method for 50 making lead arsenate the procedure illustrated diagrammatically in the drawing may be adopted. We prepare an aqueous solution of concentrated arsenic acid, preferably 68° Bé., and add to 500 pounds of this solution 100 pounds of nitric acid of 55 42° Bé. This mixture is run into the reaction tank where finely divided lead and arsenious oxid are added. These two ingredients are preferably mixed together in the dry state in the proportions of 136 60 pounds of finely divided lead and 65 pounds of arsenious oxid. This mixture is in the proper proportions for the reaction and it is added at such a rate as to prevent substantial change in the concentration of the 65 arsenic acid solution which would affect the

form of the precipitate. The rate of feeding and the temperature are also regulated to prevent foaming and the formation of undesired products. The temperature at which the reaction should be conducted depends of course upon the nature of the reagents employed and the product desired. We find that in making lead arsenate according to the above method, it is desirable to limit the temperature to between 80° C. 75 and 120° C.

Any suitable method of separating the precipitate from the liquor and for reclaiming the various reaction products may be employed, as is well known in this art. As 80 illustrated in the drawings, we may effect this separation by counter current lixiviation, such as may be had by employing the Dorr classifying system. In accordance with this process, the lead arsenate and the 85 reaction liquor are treated in the classification apparatus with a counter current of wash water, whereby the arsenic acid is washed from the precipitate. The acid may be concentrated, as by evaporation, for return to 90 the reaction tank. If desired, the nitrogen 95 oxid gases may be collected and nitric acid regenerated therefrom for return to the bath. It will be understood that this process may be made discontinuous by taking the precipitate periodically from the reaction tank and filtering and washing it with water to remove the arsenic acid, after which the filtrate and wash liquors may be evaporated to the desired concentration and 100 again used for the further formation of arsenate.

In accordance with the above method we obtain a lead arsenate which analyzes about 31% of As_2O_3 and is finely divided and of 105 very good suspension properties, settling out only very slowly when suspended in water. Moreover this material has substantially the same uniform qualities at all stages in the reaction. While we prefer to so combine the 110 ingredients and carry on the process as to form a compound of the formula of $PbHAsO_4$, it is to be noted that the proportions of arsenic acid and lead may be varied to produce either the tri-, di-, or 115 mono- basic arsenate or mixtures of these salts as may be desired.

It is furthermore clear that this method may be varied by suitable changes such as are within the knowledge of one skilled 120 in the art whereby we may produce various other arsenates, such as those of copper, zinc, iron and tin; and that the metal ions may be introduced by dissolving in the bath either a metal or any suitable compound 125 thereof.

Having thus described our invention what we claim as new and desire to secure by Letters Patent is:—

1. The method of forming a metal arse- 130

nate comprising the steps of oxidizing arsenic trioxid to arsenic acid in the presence of a concentrated solution of arsenic acid and simultaneously adding a metal element 5 of the desired arsenate and precipitating the metal arsenate by reaction with the arsenic acid, and regulating the rates of forming the arsenic acid and of precipitating the metal arsenate so as to maintain a substantially 10 uniform and high concentration of the arsenic acid.

2. The method of forming a metal arsenate, comprising the steps of preparing a bath containing a highly concentrated solution 15 of arsenic acid and a reagent capable of oxidizing arsenic trioxid, and adding arsenic trioxid and the metal element of the desired arsenate at such rates as to substantially maintain the concentration of the arsenic acid while forming a metal arsenate 20 therefrom.

3. The method of forming a metal arsenate, comprising the steps of adding arsenic trioxid and a metal corresponding to the 25 desired arsenate to a bath containing arsenic acid and a reagent capable of oxidizing the arsenic trioxid and dissolving the metal, and regulating the addition of the metal and the arsenic trioxid and the rates 30 of reaction to maintain such a concentration of the arsenic acid solution as to obtain a finely divided precipitate of substantially uniform quality.

4. The method of forming lead arsenate, 35 comprising the steps of preparing a bath of a concentrated solution of arsenic acid and nitric acid and adding finely divided lead and arsenic trioxid at such rates as to maintain the concentration of arsenic acid sub-

stantially uniform while lead arsenate is 40 being precipitated.

5. The method of forming lead arsenate, comprising the steps of preparing a solution of arsenic acid of 65° to 68° Baumé, adding nitric acid thereto, and feeding to the solution a dry mixture of finely divided lead and arsenic trioxid, maintaining the temperature of the bath at 80° C. to 120° C. and regulating the rates of reaction to produce 45 a precipitate of uniform characteristics. 50

6. The method of making a metal arsenate, comprising the steps of preparing a bath containing a concentrated solution of arsenic acid, a reagent capable of oxidizing arsenic trioxid and a solvent for the metal of the desired arsenate, adding the metal and arsenic trioxid at such rates as to maintain such a concentration of the arsenic acid while forming the metal arsenate as will 55 give a precipitate of uniform quality, replenishing the oxidizing reagent, and continuously removing the precipitated arsenate from the solution. 60

7. The method of making a lead arsenate, comprising the steps of preparing a bath 65 containing a concentrated solution of arsenic acid and nitric acid, adding finely divided lead and arsenic trioxid at such rates as to maintain the concentration of the arsenic acid while forming lead arsenate, 70 replenishing the nitric acid and continuously removing the precipitated arsenate from the solution. 75

Signed at New York city, New York, this 19th day of July, 1922.
